UNITED STATES PATENT OFFICE.

ELMER S. CURRENT, OF BEACH CITY, OHIO.

MACHINE FOR FORMING RUBBER TUBES AND THE LIKE.

1,179,077.

Specification of Letters Patent. Patented Apr. 11, 1916.

Application filed April 15, 1914. Serial No. 831,905.

To all whom it may concern:

Be it known that I, ELMER S. CURRENT, a citizen of the United States, residing at Beach City, in the county of Stark and State of Ohio, have invented certain new and useful Improvements in Machines for Forming Rubber Tubes and the like, of which the following is a specification.

My invention relates to improvements in machines for forming rubber tubes and the like and the objects of the present invention are, first, to provide a semi-automatic machine whereby the unvulcanized rubber is rolled upon a mandrel, second, to provide means whereby the mandrel together with the rubber rolled upon the mandrel is delivered to what might be termed a receiving trough, and third, to generally improve machines of the type to which this invention belongs. These objects, together with other objects, readily apparent to those skilled in the art, I attain by the construction illustrated in the accompanying drawings, although my invention may be embodied in a variety of other mechanical forms, the construction illustrated being chosen by way of example.

In the accompanying drawings—Figure 1 is an end view of what might be termed the front or feeding end of the machine. Fig. 2 is an end view of the delivery end of the machine. Fig. 3 is a top view, showing the mandrel rolling head and presser head moved into position to roll the material upon the table. Fig. 4 is a side elevation showing the presser head and mandrel rolling head in the position illustrated in Fig. 3. Fig. 5 is a diagrammatic view showing the presser and rolling head and its tracks and the position of the trip plates during the time the rolling and presser head is moved toward the left hand end of the figure. Fig. 6 is a similar view showing the rolling and presser head moving in the opposite direction. Fig. 7 is a view showing a portion of one of the side channel bar tracks or ways and illustrating the trip plates in their normal positions. Fig. 8 is a view showing a portion of the mandrel rolling and presser head or plate showing a portion of the cross base and one of the sliding blocks. Fig. 9 is a detached view of one of the heads designed for engagement with one of the mandrel pressing and rolling head actuating screw threaded shafts.

Similar numerals of reference indicate corresponding parts in all the figures of the drawings.

In the accompanying drawings, 1 represents the base or legs upon which is mounted 60 and connected the frame 2, the legs and frame constituting what might be termed the base or support of the machine proper, and is a rectangular structure formed of sufficient strength and rigidity to carry the 65 various parts both stationary and movable 68 and to hold said parts in proper relation- ship with reference to each other.

The construction of the frame proper does not have to do particularly with the inven- 70 tion, except that a suitable frame must be constructed such as common in machines of the type to which this belongs. The lower side members 3 forming a part of the frame are grooved upon their top or upper edges, 75 the groove being preferably V-shaped in cross section, such as 4. The grooved bars 3 are for the purpose of supporting and carrying the moving housings 5, which mov- 80 ing housings are provided with the verti- 85 cally sliding heads or members 6 to which are connected in any convenient and well- 90 known manner the cross bar 7, and to which cross bar is attached the mandrel rolling and pressure plate 8, which pressure plate is held 85 against rocking or tilting movement by 95 means of the brace bars 9 or their equivalents, said brace bars being connected to the mandrel pressing roll plate 8.

To the frame 2 are connected in any con- 90 venient and well known manner the channel bars 10, said channel bars being provided with upper and lower tread flanges 11 and 12. To the cross bar 7 or its equivalent are attached the downward extending bars 13, 95 and to the bottom or lower ends of the bars 13 are pivotally attached the short bars 14, which short bars carry the journaled travel- 100 ing rollers 15, said rollers being for the pur- 105 pose of supporting the vertical movable mandrel pressure and rolling head made up of the cross bar 7, the pressure plate 8 and the brace bars 9, together with the sliding heads or blocks 6. To the end members of the frame are journaled two screw threaded, 110 shafts 16, which are formed of a length to correspond substantially with the length of the frame proper and are for the purpose of imparting a reciprocating movement to the housings 5, together with the different 115

parts connected to and carried by said housings.

For the purpose of imparting rotary movement to the screw threaded shafts 16 the cross shaft 17 is provided, which cross shaft is the power shaft or the main driving shaft and is provided with the tight and loose pulleys 18 and 19, the pulley 19 being a tight pulley and the pulleys 18 loose ones, 10 and for the purpose of reversing the motion of the screw threaded shafts 16 the ordinary open and closed belts 20 and 21 are provided, which belts communicate with any source of power. The construction so far as 15 the open and closed belts and the tight and loose pulleys are concerned is common and well known and need no detailed description.

The cross or power shaft 17 is provided 20 with the worm gears 22, which worm gears mesh with the gear wheels 23 and the gear wheels 24 mesh with the gear wheels 25, which gear wheels are connected to the screw threaded shafts 16. I have illustrated in what 25 might be termed a conventional way the gearing for imparting rotary motion to the screw threaded shafts 16, but the specific gearing is immaterial, except that the gearing must be such as to rotate the screw 30 threaded shafts in unison, and in the same direction at the same time. For the purpose of imparting a reciprocating movement to the housings 5, said housings are provided with the blocks or heads 26, the inner ends 35 or edges of said blocks being provided with screw threaded semi-circular grooves 27, the pitch of the grooves corresponding with the pitch of the screw threads upon the shaft 16.

For the purpose of bringing about the 40 proper adjustment for the blocks 26 with reference to each other, the blocks are provided with the flanges 28, said flanges being provided with the recesses 29 and the flanges 28 adjustably connected to the housings 5 45 by means of suitable lug bolts 30 or their equivalents. It will be understood that by the rotation of the screw threaded shafts 16 and by reason of the blocks 26 and the screw threaded grooves 27 movement will be imparted to the housings 5, the direction of movement being governed by the direction of rotation of the screw threaded shafts 16.

In the manufacture of tubes by the use 55 of my present invention a metallic mandrel such as 31 is used, which mandrel is of a length to correspond with the length of the tube and owing to the fact that the tubes must be formed of a length sufficient to produce the inner tube of a tire, the full length 60 must necessarily be about ten or twelve feet long, reference of course, being had to the diameter of a wheel, upon which a completed tire is to be placed. Upon this long metallic mandrel is first rolled a sheet or 65 sheets of unvulcanized rubber, and it is with

the rolling of this unvulcanized rubber upon the mandrel that this invention has to do.

To the frame proper is attached a table 32, which table is formed of a width equal to about one-third of the length of the machine proper. The table 32 is preferably covered with cloth as indicated by the numeral 32^a, and upon this cloth covering is placed the unvulcanized rubber designed to be wound upon the mandrel, the initiative 75 arrangement of the mandrel and the unvulcanized sheet of rubber being illustrated in Fig. 3, in which figure is illustrated the position of the movable pressure or rolling plate 8, together with the different parts, 80 such as the housings and the parts carried by said housings.

It is well understood by those skilled in the art, that unvulcanized rubber will more readily adhere to a metallic surface than it 85 will to a fibrous surface, hence the necessity of covering the table 32 with the fibrous cover 32^a.

The operation of the machine is substantially as follows: Assuming that the mandrel, the sheet of rubber and the rolling and pressing plate are in the positions shown in Fig. 1, rotary motion is imparted to the screw threaded shafts 16 and in the direction to move the pressure plate 8 over the 95 table. In order that as the rolling and pressure plate 8 may be brought down upon the mandrel during the time the unvulcanized rubber is being placed upon the mandrel the channel bars are each provided with 100 the inclines 34 and upon which inclines the traveling rollers 15 move upon, thereby allowing the presser plate 8 together with the movable parts connected to said presser plate to move downward, thereby placing 105 the weight of the presser plate upon the mandrel, or in other words the mandrel constitutes what might be termed the supports 110 for said presser plate and its different parts.

It will be understood that the traveling 115 wheels should not come in contact with the lower tread flange 12 during the time the presser plate is upon the mandrel, otherwise the weight of the presser plate would be removed from the mandrel, and in order to provide for this condition the arms 13 should be formed of such a length that the traveling wheels 15 will be spaced a short 120 distance from the upper faces of the lower tread flanges as best illustrated in Fig. 6.

It will be understood that when the presser plate 8 together with its different parts is moved in the opposite direction or during its backward movement it should be elevated so that there could be no possibility of imparting a backward rolling movement to the mandrel and in order to provide means for thus elevating the head, the hinged tread sections 35 are provided and as the traveling wheels 15 move under said 125 130

hinged members or treads, they will elevate said treads as best illustrated in Fig. 6 and after the wheels 15 have fully passed said tread section 35, the same are free to fall by gravity into the position illustrated in Fig. 5, and when a backward movement is imparted to the pressure plate 8 said wheels will ride up and upon the hinged member treads 35, and then ride upon the upper tread 11. When the pressure plate 8 has been moved backward to nearly its limit the traveling wheels 15 come in contact with the hinged sections 36, which hinged sections are normally held in inclined positions and practically parallel with the inclined treads 34 and as the wheels 15 strike said hinged plates or treads 36, they will be pressed down and into the position illustrated in Fig. 5, said hinged portions forming parts of what might be termed the upper tread flanges 11, said hinged section taking the place of that portion of the tread flange which they occupy.

After the traveling wheels 15 have fully passed the hinged sections 36 they are automatically brought into their normal positions by means of the springs 37, which springs are of the usual construction and need no specific description, except that they must be so formed and connected that they will normally hold the hinged members 36 as illustrated in Fig. 7. Upon the return movement of the presser plate together with the different parts belonging thereto the wheels 15 will ride down the inclines 34 and under the hinged members 36 as best illustrated in dotted lines, Fig. 6.

As the mandrel is rolled along upon the table 32 by the forward movement of the presser plate 8 it will be brought to the delivery edge of said table, at which time the unvulcanized sheet or sheets of rubber has been properly wrapped or placed upon the mandrel and deposited upon the inclined bars or strips 38, the lower ends of said bars or strips being provided with the trough shaped portions 39, which trough shaped portions receive the mandrel, together with the material wrapped or rolled thereon. For the purpose of preventing the mandrel from dropping off from the extreme ends of the inclined strips or bars 38, a cross or stop bar 40 is provided, which stop or cross bar also forms a support for the strips or bars 38.

It is well understood that before the cross wrapping of the unvulcanized rubber is put upon the mandrel, said unvulcanized sheets should be covered with muslin, which cross wrapping and the purpose thereof has been fully described in my former application for patent for improvement in cross wrapping machines, filed April 4, 1914, Serial No. 829,437. The wrapping of the canvas upon the unvulcanized rubber is

placed upon the mandrel and is brought about in the same manner and by the same kind of a machine as herein described, the canvas wrapping machine being, and is a duplication of the machine here illustrated, and in use the mandrel after receiving the sheet or sheets of unvulcanized rubber is placed in the second machine, or if desired the same machine may be used for wrapping the canvas, but I prefer to use two machines so that the two operations may be what might be termed continuous or practically so, it being understood that manual labor must be employed to take the mandrel from one machine and place it upon another.

For the purpose of providing means for elevating the presser plate together with the different parts carried thereby, the shaft, 41 is provided, which shaft may be journaled in the housings 5 or in the caps 42 and upon said shaft are located the heads 43, one of said heads being provided with the operating lever 44 and to the heads 43 are connected the cords or chains 45, said cords or chains also being connected to the sliding heads or blocks 6. In order that the proper amount of pressure may be given to the mandrel and to the unvulcanized rubber during the time the said unvulcanized rubber is being placed or wrapped upon the mandrel, suitable weights 46 may be used, said weights being connected to the sliding heads 6 by means of the hooked rods 47 and the pins 48.

For the purpose of automatically shifting the open and closed belts 20 and 21, the sliding bar 48^a is provided, which sliding bar is alternately actuated by means of the strike blocks 49, which are connected to the bar 48^a in any convenient and well known manner, said blocks being alternately struck by the housings 5. This construction being common and also illustrated in my former application above referred to no further detailed description of the reverse motion mechanism is deemed necessary.

It will be understood that in use the sheet of unvulcanized rubber 32^b should be formed of a width and length to form a tube of the desired length and to give to the tube the desired thickness reference being had to the thickness of the sheet of rubber and as to the number of convolutions or wraps to be given to the sheet. It will also be understood that by providing the weights 46 any desired amount of pressure may be given to the unvulcanized rubber during the time it is being wrapped upon the mandrel.

Having fully described my invention what I claim as new and desire to secure by Letters Patent is—

1. In a machine for forming rubber tubes and the like, the combination of a suitable frame, a table fixed to and carried by said

- frame, a mandrel adapted to roll upon said table, tracks or ways carried by the frame, housings movably mounted upon the tracks or ways, means for imparting reciprocating movement to said housings, a pressure plate adjustably connected to and carried by the housings, downward extending bars carried by the pressure plate, said downward extending bars provided at their lower ends with rollers, channel bars fixed to the frame, said channel bars provided with spaced upper and lower tread flanges, hinged plates connected to the upper tread flanges of the channel bars and inclined flanges located between the upper and lower flanges of the channel bars.
2. In a machine of the class described, the combination of a frame, a table fixed to the frame, a mandrel adapted to roll upon said table, housings, tracks or ways adapted to support said housings, means for imparting reciprocating movement to the housings, a pressure plate carried by the housings and adapted for vertical movement with reference to the housings, and means for imparting vertical movement during the reciprocating movements of the housings.
3. In a machine of the class described, the combination of a frame, a table fixed to and carried by said frame, a mandrel adapted to roll upon said table, housings, tracks or ways adapted to support said housings, means for moving said housings upon said tracks or ways, a pressure plate carried by the housings and adapted to rest upon the mandrel, said pressure plate connected to vertically movable guide blocks, said pressure plate mounted upon traveling rollers, upper and lower spaced tread flanges adapted to support said traveling rollers and the pressure plate and means for shifting the tread of the rollers from the upper to the lower tread flanges.
4. In a machine of the class described, the combination of a frame, a table fixed to and carried by said frame, a mandrel adapted to roll upon said table, housings, tracks or ways adapted to support said housings, means for moving said housings upon said tracks or ways, a pressure plate carried by the housings and adapted to rest upon the mandrel, said pressure plate connected to vertically movable guide blocks, said pressure plate mounted upon traveling rollers, upper and lower spaced tread flanges adapted to support said traveling rollers and the pressure plate, and means for shifting the tread of the rollers from the lower to the upper tread flanges.
5. In a machine of the class described, the combination of a frame, a table fixed to and carried by said frame, a mandrel adapted to roll upon said table, housings, tracks or ways adapted to support said housings, means for moving said housings upon said tracks or ways, a pressure plate carried by the housings and adapted to rest upon the mandrel, said pressure plate connected to vertically movable guide blocks, said pressure plate mounted upon traveling rollers, upper and lower spaced tread flanges adapted to support said traveling rollers and the pressure plate, means for shifting the tread of the rollers from the lower to the upper tread flanges, and a series of spaced bars adapted to receive the mandrel.
6. In a machine of the class described, the combination of a frame, a table fixed to and carried by said frame, a mandrel adapted to roll upon said table, housings, tracks or ways adapted to support said housings, means for moving said housings upon said tracks or ways in opposite directions, a pressure plate carried by the housings and adapted when in a lowered position to rest upon the mandrel, said pressure plate connected to vertically movable guide blocks, said pressure plate mounted upon traveling rollers, upper and lower spaced tread flanges adapted to support said traveling rollers, and the pressure plate, means for shifting the rollers and the pressure plate vertically, a series of inclined spaced bars adapted to carry the mandrel.
7. In a machine of the class described, the combination of a frame, a table fixed to and carried by said frame, a mandrel adapted to roll upon said table, housings, tracks or ways adapted to support said housings, means for moving said housings upon said tracks or ways in opposite directions, a pressure plate carried by the housings and adapted when in a lowered position to rest upon the mandrel, said pressure plate connected to vertically movable guide blocks, said pressure plate mounted upon traveling rollers, upper and lower spaced tread flanges adapted to support said traveling rollers, and the pressure plate, means for shifting the rollers and the pressure plate vertically, a series of inclined spaced bars adapted to carry the mandrel, the lower ends of said spaced bars provided with trough shaped portions.
8. In a machine of the class described, the combination of a frame, a table fixed to and carried by said frame, a mandrel adapted to roll upon said table, housings, tracks or ways adapted to support said housings, means for moving said housings upon said tracks or ways in opposite directions, a pressure plate carried by the housings and adapted when in a lowered position to rest upon the mandrel, said pressure plate connected to vertically movable guide blocks, said pressure plate mounted upon traveling rollers, upper and lower spaced tread flanges adapted to support said traveling rollers and the pressure plate, means for shifting the rollers and the pressure plate vertically,

a series of inclined spaced bars adapted to carry the mandrel, the lower ends of said spaced bars provided with trough shaped portions, and a stop bar adapted for contact with the mandrel.

- 5 9. In a machine of the class described, the combination of a frame, a table fixed to the frame, a mandrel adapted to roll upon the table, housings, tracks or ways adapted 10 to support said housings, means for moving and guiding said housings, a pressure plate carried by the housings and adapted for contact with the mandrel and means for moving said pressure plate to and from the mandrel.
- 15 10. In a machine of the class described, the combination of a frame, a table fixed to the frame, a mandrel adapted to roll upon the table, housings, tracks or ways adapted to support said housings, means for moving 20 and guiding said housings, a pressure plate carried by the housings and adapted for contact with the mandrel, and means for al-

ternately moving said pressure plate to and from the mandrel.

11. In a machine of the class described, 25 the combination of a frame, a table fixed to the frame, a mandrel adapted to roll upon the table, housings, tracks or ways adapted to support said housings, means for moving and guiding said housings, a pressure plate 30 carried by the housings and adapted for contact with the mandrel and means for moving said pressure plate to and from the mandrel, and inclined bars extended from the table and adapted to receive the mandrel, 35 and means for holding the mandrel upon said inclined bars.

In testimony that I claim the above, I have hereunto subscribed my name in the presence of two witnesses.
